UNITED STATES PATENT OFFICE.

JOHN J. KRAMER AND HERMAN SMERLING, OF LA CROSSE, WISCONSIN, ASSIGNEES TO
LA CROSSE RUBBER MILLS COMPANY, OF LA CROSSE, WISCONSIN.

BOOT-STRIPPING DEVICE.

1,299,399.

Specification of Letters Patent.

Patented Apr. 1, 1919.

Application filed August 12, 1918. Serial No. 249,537.

To all whom it may concern:

Be it known that we, JOHN J. KRAMER and HERMAN SMERLING, the former a citizen of the United States, and the latter a subject of the Emperor of Germany, residing at La Crosse, in the county of La Crosse and State of Wisconsin, have invented certain new and useful Improvements in Boot-Stripping Devices; and we do declare the following to be a full, clear, and exact description of the invention, such as will enable others skilled in the art to which it appertains to make and use the same.

In the manufacture of rubber boots, it is common practice to build the boot up upon lasts formed of several sections, and with the method now used, considerable expenditure of time and labor is necessary in stripping the completed boot from the last, the object of this invention being to provide a simple and inexpensive device which will quickly and easily remove the last from the boot; and with this object in view, the invention resides in the device hereinafter fully described and claimed, reference being made to the accompanying drawings.

Figure 1 is a perspective view showing the manner in which the last remover is used.

Fig. 2 is a vertical sectional view of the device.

Fig. 3 is a partial top plan showing the manner in which the boot is held in place.

Fig. 4 is a detail horizontal section on the plane of the line 4—4 of Fig. 2.

Fig. 5 is a detail perspective view of the upper end of the pulling lever and the link which connects it with the last.

In the drawings above briefly described, the numeral 1 designates a vertical leg preferably formed of a single metal bar with its lower end bent laterally at 2 and its upper end extended laterally in the opposite direction at 3 to provide a horizontal arm upon which a boot supporting member, preferably in the form of a shelf 4 is mounted. The support 4, or rather the arm 3 thereof is adapted to rest on a table or work bench 5 and in order to retain it properly in place, a foot plate 6 is connected to the lower end

of the leg 1 by an arm or the like 7, it being intended that the operator shall place one foot upon the plate 6.

The free end of arm 3 is bent or otherwise turned upwardly to provide a vertical arm 8 whose upper end is decreased in width to form an upstanding lug 9. A right angular metal bar 10 is secured to the arm 8 and forms a seat member to receive the heel portion 11 of the boot 12, and in order to hold the boot properly engaged with said seat, a strap 13 is secured at one end to the support 4, said strap being provided on its other end with a plurality of hooks 14 for engagement with the lug 9 after passage of the strap over the instep of the boot. By this means, the boot is effectively held in place upon the support 4 and may be easily applied to said support or removed therefrom, with the expenditure of little time.

A pull member in the form of a vertical arm 15, preferably formed of metal, is pivoted at 16 to the front end of the forwardly projecting portion 2 of the leg 1, the upper end of said arm 15 being provided with a notch 17 to receive a pull link or rod 18, the outer end of said rod having an abutment 19 threaded thereon for adjustment longitudinally thereof, while the inner end of the rod in question is provided with a hook 20 for engagement with a pin or the like 21 at the end of the last 22. The last is formed of several sections in the usual manner and it will be obvious that by pulling the arm 15 outwardly, the individual sections may be removed one at a time. For operating the arm 15 in the required manner, a lever 23 is fulcrumed to a U-shaped bracket 24 secured to the upper end of the leg 1, the fulcrum of said lever preferably consisting of a rock shaft 25 journaled in the arms of said bracket, said arms straddling the leg 1 and extending forwardly toward the arm 15. The shaft 25 is provided with a crank arm or cam 26 for engagement with the inner side of the arm 15, whereby a downward push on the hand lever 23 will so actuate said crank arm or cam as to force the arm 15 out- 1

- wardly, thus pulling the rod 18 to withdraw the last from the boot. A coiled spring 27 is preferably employed to return the lever 23 to its inoperative position, another spring 28 is used to normally swing the arm 15 rearwardly, and a yoke 29 is secured to the leg 1 to limit the outward movement of the arm 15 and to guide said arm in its operation.
- 10 The device has been successfully used in the factory of a well known rubber company and has proven a valuable asset, effecting a great saving in time and labor. Since excellent results have been obtained 15 from the arrangement shown and described, it is by preference followed, but within the scope of the invention as claimed, considerable latitude is allowed for making such minor changes as occasion may dictate.
- 15 20 We claim:
1. A device for removing lasts from boots comprising a leg adapted to rest on the floor, a boot support extending from said leg and adapted to rest on a table, means for holding a boot on said support, and means for pulling the last from the boot.
  2. A device for removing lasts from boots comprising a leg adapted to rest on the floor, a boot support extending from said leg and 30 adapted to rest on a table, means for holding a boot on said support, a vertical arm pivoted at its lower end to said leg and adapted for connection at its upper end with the last, and means for operating said arm 35 to withdraw the last.
  3. A device for removing lasts from boots comprising a leg adapted to rest on the floor, a boot support extending from said leg and adapted to rest on a table, means 40 for holding a boot on said support, a vertical arm pivoted at its lower end to said leg and adapted for connection at its upper end with the last, and a lever fulcrumed on said leg and having a cam for operating said 45 arm to withdraw the last.
  4. A structure as specified in claim 1, and a foot plate on the lower end of said leg to receive the operator's foot, whereby to hold the device effectively in place.
  5. A device for removing lasts from boots comprising a leg adapted to rest on the floor and having its upper end extended laterally to provide an arm to rest on a table, a boot support secured to said arm, the end of the 55 latter being turned upwardly at one end of said support, boot holding means coöperating with said upwardly turned end of said arm, and means for pulling the last from the boot.
  6. A structure as specified in claim 5, said boot holding means comprising a strap secured at one end to said support and having a hook at its other end engaging said upturned end of the arm.
  7. A structure as specified in claim 5, together with an angular seat member extending from said upturned end of said arm to receive the heel of the boot.
  8. A device for removing lasts from boots comprising a leg extended laterally at its upper and lower ends, the upper extension extending rearwardly and the lower extension forwardly, a boot support secured to said upper extension of the leg and having boot holding means, a vertical arm pivoted to the lower extension of said leg, said arm rising in front of said support and being adapted for connection to the last, and means on said leg for operating said arm to withdraw the last.
  9. A structure as specified in claim 8, the operating means of said arm consisting of a hand lever fulcrumed on said leg and having a cam contacting with the arm.
  10. A device for removing lasts from boots, comprising a horizontal boot supporting shelf upon which the boot is laid, an arm rising from one end of said shelf for contact with the heel bottom, means coacting with said arm for holding the boot on said shelf, and means for withdrawing the last.
  11. A structure as specified in claim 10, said boot holding means comprising a strap anchored at one end to said shelf and having a hook on its other end for engagement with said arm.
  12. A structure as specified in claim 10, and a lateral projection extending horizontally from said arm to engage the rear edge of the boot heel.
  13. A device for removing lasts from boots comprising a vertical leg formed of a single metal bar bent forwardly at its lower end and bent rearwardly at its upper end to form an arm, a boot supporting shelf mounted on said arm, the end of the arm being turned upwardly at the end of said shelf, a strap secured to said shelf at one end and having a hook at its other end for engagement with said upturned end of the arm, whereby to secure the boot on the shelf, a foot plate below and connected to said leg, a vertical arm pivoted to and rising from the forwardly bent end of said leg, the upper end of said last named arm having a notch, a pull rod adapted for reception in said notch, one end of said rod having means for engagement with the last and the other end of said rod having an adjustable abutment 110 against which said pivoted arm bears, a U-shaped bracket straddling and secured to the upper end of said leg, a rock shaft journaled in the arms of said bracket and having a cam for forcing the pivoted arm forwardly, a hand lever secured to said rock shaft for operating the same to actuate said cam, and a yoke secured to said leg and sur-

rounding said pivoted arm to guide the same.

14. A device for removing lasts from boots comprising boot holding means, a pull member spaced from said means, means for moving said pull member away from said holding means, a pull rod having means for

engagement with the last, and an abutment on said rod to engage said pull member, the latter having a notch to receive said rod. 10

In testimony whereof we have hereunto set our hands.

JOHN J. KRAMER.
HERMAN SMERLING.
